(57) **CLAIM**

The ornamental design of an in-sink dishwasher, as shown and described.

DESCRIPTION

FIG. 1 is a front perspective view of the in-sink dishwasher showing the new design;

FIG. 2 is a top plan view thereof;

FIG. 3 is a top perspective view thereof with the lid shown open;

FIG. 4 is a front elevation view thereof with the lid shown open; and,

FIG. 5 is a rear elevation view thereof with the lid shown open.

The broken lines shown are for illustrative purposes only and form no part of the claimed design.
